AIR PREHEATER

Original application filed January 24, 1930, Serial No. 423,051. Divided and this application filed March 24, 1931. Serial No. 524,832.

This application is a division of our co-pending application Serial No. 423,051, filed January 24th, 1930.

Our invention relates to air preheaters and more particularly to air preheaters for heating air for combustion in a boiler plant by means of the products of combustion or flue gases leaving the boiler plant.

Amongst the objects of the invention are: to provide means for regulating the flow of air through an air preheater so as to maintain proper temperature conditions; to prevent formation of moisture within an air preheater; to selectively feed air to different sections of an air preheater to obtain predetermined temperatures of fluids; to coordinate the flow of air to the flow of products of combustion through an air preheater so as to obtain desired temperatures of heated air and to obtain desired temperatures of products of combustion; to regulate air flow through an air preheater so as to obtain desired and preferably constant temperature of air to be supplied to fuel pulverizing apparatus and like devices; to automatically regulate the flow of air through an air preheater; to automatically regulate the flow of air through an air preheater to obtain desired conditions of temperature and to prevent formation of moisture within an air preheater; to provide an air preheater in combination with a plurality of paths or conduits for flow of air to a furnace and to regulate the relative quantities of air flowing in the various paths to obtain the best operating conditions; and other objects as will appear.

The nature and advantages of the invention and the various phases thereof will be come apparent from consideration of the following specification taken in conjunction with the accompanying drawing which forms a part of this specification, and on which:

Fig. 1 is a side or elevational view of an air preheater embodying the invention; and

Fig. 2 is a cross-sectional, horizontal view taken on the line 2—2 of Fig. 1.

The air preheater is indicated, in general, by reference character 10. It comprises

four sections, 11, 12, 13 and 14. Each section comprises side walls 15 and 16. Within each section are partitions 17 consisting of vertically arranged parallel plates. The plates are arranged to form alternate spaces separated from each other. For this purpose the plates are joined at the sides as shown in Fig. 2 in pairs, and each plate of a pair is joined at the top to the adjacent plate of the next pair, as shown for example, in U. S. Patent No. 1,727,124, granted September 3rd, 1929, to William Lonsdale.

Between the sections are intermediate conduits or sections 19 which connect corresponding spaces of the different sections to permit flow of fluid, specifically gas, serially through the sections, vertically, in one set of alternately disposed spaces. The sides of the sections are connected by intermediate conduits or return bends 20, connecting the other set of spaces for serial flow of fluid horizontally through the sections. It will be seen that the gases (air) flowing horizontally are separated from the gases (products of combustion) flowing vertically downward. Products of combustion are supplied to the air preheater at the top through connection 21 and flow straight downwardly through all the sections of the air preheater, passing through the connections 19 into and through the soot hopper 34 and thence into the flue 35.

Referring to Fig. 2, the products of combustion pass through the spaces 24. Air is admitted to the preheater by means of the lower conduit 23, passes transversely through section 14, thence through the intermediate conduit 20 connecting section 14 with section 13, thence transversely through section 13, thence through the right-hand conduit 20, thence transversely through section 12, thence through the upper left-hand intermediate conduit 20, thence transversely through the upper section 11 and thence to the boiler in which the heated air is to be used. Referring further to Fig. 2, it will be seen that the air passes through the spaces 22. It will also be seen that the air and the products of combustion do not come into direct contact.

With the arrangement thus far described, wherein products of combustion pass through all of the sections of the air preheater and air passes through all of the sections of the air preheater, it is possible that, at certain loads, the temperature of the products of combustion would be lowered to below what is known as the dew-point, at which point of temperature, steam, carried

- 16 in the products of combustion, condenses and precipitates. It is desirable to avoid the lowering of the temperature of the products of combustion to the dew-point in order to prevent precipitation of moisture, particularly with certain fuels of high sulphur content, since water and the sulphur dioxide resulting from the combustion of such fuels combine to form sulphuric acid, which is highly corrosive. Corrosion causes 20 uneven surfaces of metal. With moisture present, ash in the products of combustion tends to deposit and form a sticky mass on the uneven surface produced by corrosion. Such sticky deposit may form a distinct coating on the metal and may cause further deposits. The passages of air preheaters are small in order to obtain efficiency of heat transfer and in order to economize on space. The formation of such deposits due to the 25 presence of moisture, corrosion and ash content of the products of combustion may materially diminish the cross-sectional area of flow in the passages between the plates of the preheater, that is, between partitions 17. Corrosion itself is undesirable because it decreases the life of apparatus, but, in this 30 case, there is the added disadvantage of the decrease of cross-sectional area of flow of the preheater passages. This decrease of 35 flow area carries with it several disadvantages in that the heat transfer capacity of the plates is reduced; the draft loss is increased, as a result of which more power is necessary to operate the fan to draw the 40 gases through the preheater; and, in the case of plants already equipped with fans of given capacity, the accumulation of deposits 45 may reduce the capacity of the steam generating unit due to the inability of the fans to draw the products of combustion through 50 the preheater at a sufficient rate.

To overcome this difficulty we have provided a by-pass conduit 25, a damper or valve 26 in by-pass conduit 25, and a damper or valve 27 in the intermediate conduit 20 between sections 13 and 14. By-pass conduit 25 connects the air supply conduit 23 with the intermediate conduit 20 between sections 12 and 13. By closing damper 27 55 and opening damper 26, all the air to be heated passes directly to section 12. Damper 27 may be used to prevent recirculation of air around sections 13 and 14 when the damper 26 is open. By partially opening 60 damper 26 and having damper 27 open, or

partially open, some of the air will pass through all the sections and some will pass only through two sections. The proportion of air passing through all sections and bypassing some sections can be regulated by 70 proper manipulation of the dampers 26 and 27.

If the air is cold or if other conditions prevail such that there is a lowering of the temperature of the products of combustion 75 to or below the dew-point, the air can be passed through by-pass conduit 25 in whole or in part, and thus a temperature can be maintained in the outlet for the products of combustion which is above the dew-point. By regulating the dampers it is possible to obtain a constant temperature in the products of combustion leaving the air preheater, or in any degree, within limitations, of variation of temperature desired, independently or in spite of variations of load. 80

It will be readily seen that one or more of the sections may be by-passed in this way. The conduit 25 may be connected between conduit 23 and the air inlet for section 13, or even with the air inlet for section 11. 85

The damper 26 may be interconnected with the damper 27 and they may be automatically controlled in accordance with the 90 temperature of products of combustion leaving the preheater.

It will be understood that variations may be made within the spirit and scope of the invention. 95

What we claim is:

1. Apparatus for heating air by products of combustion comprising a plurality of sections, each having closely spaced plates connected to form two sets of separated spaces, means to connect the sections for flow of products of combustion serially through the sections in one set of separated spaces, lateral return bends connecting the sections for passage of air serially through the sections 105 in the other set of separated spaces, an air supply conduit, an air discharge conduit, means to supply and discharge products of combustion, a by-pass connection between the air supply conduit and one of the return 110 bends, and a damper in said by-pass connection. 115

2. Apparatus for heating air by products of combustion comprising a plurality of sections, each having closely spaced plates 120 connected to form two sets of separated spaces, means to connect the sections for flow of products of combustion serially through the sections in one set of separated spaces, lateral return bends connecting the sections 125 for passage of air serially through the sections in the other set of separated spaces, an air supply conduit, an air discharge conduit, means to supply and discharge products of combustion, a by-pass connection be- 130

tween the air supply conduit and a return bend connected to the next to the last section in the line of flow of products of combustion, and a damper in said by-pass connection.

5 3. Apparatus for heating air by products of combustion comprising a plurality of sections, each having closely spaced plates connected to form two sets of separated spaces, means to connect the sections for flow of 10 products of combustion serially through the sections in one set of separated spaces, lateral return bends connecting the sections for passage of air serially through the sections in the other set of separated spaces, an air supply conduit, an air discharge conduit, means to supply and discharge products of combustion, a by-pass connection between the air supply conduit and the return bend connecting the second and third sections in the line 20 of air flow, a damper in said by-pass connection, and means to cut off flow through the return bend connecting the first and second sections in the line of air flow.

4. Apparatus for heating air by products 25 of combustion comprising a plurality of sections, each having closely spaced plates connected to form two sets of separated spaces, means to connect the sections for flow of products of combustion serially through the sections in one set of separated spaces, lateral return bends connecting the sections for passage of air serially through the sections in the other set of separated spaces, and means to supply air to one or the other or 30 both of the first and third sections in the line of flow of air.

5. In a flue gas preheater of the plate type including a plurality of sections, the method 40 of controlling the temperature of flue gases leaving the preheater which comprises supplying air to the one or the other or both of the first and third sections in the line of air flow to maintain the temperature of the flue gases above the dew point.

45 6. Apparatus for heating air by products of combustion comprising a plurality of sections, each section having a passage for the flow of products of combustion therethrough and a passage for the flow of air there- 50 through out of contact with said products of combustion, means for connecting the sections so that the products of combustion flow serially through the several sections, conduits connecting the sections and the air passages so that the air flows serially through 55 the several sections, an air supply conduit, an air discharge conduit, means to supply and discharge products of combustion, a by- 60 pass connection between the air supply conduit and one of the conduits connecting said air passages, a damper in said by-pass connection, and a damper for controlling the flow of air through the conduit connecting the air passages in the sections which are 65 by-passed.

7. Apparatus for heating air by products of combustion comprising a plurality of sections, each section having a passage for the flow of products of combustion therethrough and a passage for the flow of air therethrough out of contact with said products of combustion, means for connecting the sections so that the products of combustion flow serially through the several sections, conduits connecting the sections and the air passages so that the air flows serially through the several sections, an air supply conduit, an air discharge conduit, means to supply and discharge products of combustion, and means to supply air to one or the other or 80 both of two sections separated by one or more other sections.

8. In a flue gas preheater having a plurality of sections, each provided with a passage for the flow of products of combustion therethrough and a passage for the flow of air therethrough out of contact with the products of combustion, the products of combustion and air passages respectively of the several sections being connected in series, the 85 method of controlling the temperature of flue gases leaving the preheater which comprises supplying air to two sections separated by one or more other sections to maintain the temperature of the flue gases 90 above the dew point.

In testimony whereof, we have hereunto affixed our signatures.
